UNITED STATES PATENT OFFICE.

FREDERICK WILKINSON, OF REDDISH, COUNTY OF LANCASTER, ENGLAND.

CARDING-ENGINE.

SPECIFICATION forming part of Letters Patent No. 392,247, dated November 6, 1888.

Application filed October 18, 1887. Serial No. 252,760 (No model.) Patented in England February 18, 1886, No. 2,366; in France November 19, 1886, No. 179,766; in Belgium November 20, 1886, No. 75,309, and in Germany December 5, 1886, No. 40,500.

To all whom it may concern:

Be it known that I, FREDERICK WILKINSON, a subject of the Queen of Great Britain, residing at Reddish, in the county of Lancaster, England, have invented certain Improvements in Carding-Engines, (for which I have obtained Letters Patent in Great Britain, dated February 18, 1886, No. 2,366; in France, dated November 19, 1886, No. 179,766; in Belgium, dated November 20, 1886, No. 75,309, and in Germany, dated December 5, 1886, No. 40,500,) of which the following is a specification.

My invention relates to improvements in traveling flat carding-engines; and the chief object of my improvements is to reduce the wear on the ends of the traveling flats, and also to facilitate the adjustment of their clothing to the main cylinder.

In carrying my invention into effect I dispense with the ordinary flexible bend, and I employ instead on each side of the machine a spider-wheel or disk-wheel, which is mounted upon a flanged bush fitted over the shaft of the main cylinder. The flange of this bush is slotted and bolted to a fixed part in such manner that the bush and the wheel can be adjusted concentrically with the periphery of the main cylinder and independently of the shaft.

A feature of my invention is to give a slow revolving motion to the spider-wheel, so that the surface speed of the wheel equals or approximates the speed at which the flats travel, and thus there is no friction between the flats and the wheel. Consequently a coating of any suitable material could be laid on the periphery of the wheel. After the flats have been set to the clothing of the main cylinder it is necessary to turn, grind, or otherwise reduce the diameter of the wheel whenever the cylinder-clothing is reground.

In order that my invention may be fully understood and readily carried into effect, I will describe the accompanying sheet of drawings, reference being had to the figures and letters marked thereon.

Figure 1 is a side elevation of part of a carding-engine to which my improvements have been applied. Fig. 2 is a transverse vertical

section of the sides of the same, and Fig. 3 is a detail view of the flanged and slotted bush.

In the views, A designates the main cylinder, and b the cylinder-shaft supported in bearings c' in the blocks or pedestals c. 55 d is the engine bend or framing; d', the lower framing, and e part of the traveling flats. On each side of the machine is a wheel, f, in this case a spider-wheel, which I employ according to my invention, fitted and free to revolve upon a flanged bush, g, secured by bolts g' to the pedestal c. These rods pass through slots g" in said bush. On the periphery of the wheel f, I propose to secure a ring of metal, f', or a layer or coating of any suitable material, 65 on which the ends of the flats are supported. The spider-wheel f is provided with worm-teeth f" on its face, and is caused to revolve at the same or approximately the same surface speed as the speed at which the flats travel 70 by means of a worm on a shaft, h, having its bearings in brackets h', fixed to said bend or framing. This worm-shaft is provided with belt-pulleys h" h", either one of which may be connected at will to one of a corresponding 75 pair of pulleys, h" h", on a driving-shaft, H. As shown, the connection is between pulley h" and pulley h" by means of an endless belt, h". The driving-shaft H may receive motion directly from an engine, or through any convenient arrangement of intermediate mechanism. 80

When the card-clothing on the main cylinder a has been ground, it is necessary to reduce the diameter of the spider-wheel f in order to adjust the flats. This may be effected in various ways, but preferably by grinding the ring f' on the periphery of the wheel by means of a revolving grinding roller or cutter, i, held in an adjustable bracket, j, secured to the bend d. When, however, instead of the metal ring 85 f', the periphery of the wheel is covered or coated with other material—such as paper—the diameter of the wheel might be reduced by cutting and trimming or otherwise removing one or more layers of such material. 90

When the bearings of the shaft b wear, the periphery of the wheel f may be adjusted concentrically with the periphery of the main cylinder by slackening the bolts g' and regulating the position of the bush. 95

In referring to the drawings I have described one wheel, *f*, only; but it is obvious that there would be two exactly similar wheels *f* mounted adjustably, as described, one on either side 5 of the machine.

What I claim as my invention, and desire to secure by Letters Patent of the United States, is—

1. The traveling flats and main cylinder of 10 a carding-engine, in combination with two wheels or disks mounted one on each side of said engine, and gearing for rotating said wheels continuously at a surface speed approximately equal to that of the flats, substantially as set forth.

2. The traveling flats and main cylinder of 15 a carding-engine, in combination with two wheels or disks mounted one at each side of said engine, gearing for rotating said wheels, 20 and devices for adjusting the said wheels to make them concentric with the main cylinder, substantially as set forth.

3. In combination with the traveling flats,

the main cylinder, and the pedestals, a carding-engine, the wheels *f* on opposite sides of 25 said engine, the shaft on which said wheels are mounted, the slotted bushes *g* between said wheels and said shaft, and the bolts which pass through the slots of said bushes into the pedestals, substantially as set forth.

4. The traveling flats and main cylinder of 30 a carding-engine, in combination with the wheels *f*, arranged one on each side of said engine, the rings *f'*, secured to said wheels, the slotted bushes *g*, bolts *g'*, the supporting-frame, 35 and gearing for rotating the wheels *f*, substantially as set forth.

In testimony that I claim the foregoing as my invention I have signed my name, in presence of two witnesses, this 7th day of October, 40 1887.

FREDERICK WILKINSON.
